UNITED STATES PATENT OFFICE

165,598

DEVICE FOR TRANSPORTING BEDRIDDEN PATIENTS

George B. Nelson, Chicago, Ill.

Application September 9, 1949, Serial No. 4,925

Term of patent 14 years

(Cl. D15—1)

To all whom it may concern:

Be it known that I, George B. Nelson, a citizen of the United States, residing at Chicago, in the county of Cook and State of Illinois, have invented a new, original, and ornamental Design for a Device for Transporting Bedridden Patients, of which the following is a specification, reference being had to the accompanying drawing, forming a part thereof.

In the drawing:

The figure is a perspective view of my device for transporting bedridden patients, embodying my new design.

I claim:

The ornamental design for a device for transporting bedridden patients, as shown.

GEORGE B. NELSON.
